UNITED STATES PATENT OFFICE.

NAHUM ELLEN LUBOSHEZ, OF LONDON, ENGLAND, ASSIGNOR TO EASTMAN KODAK COMPANY, OF ROCHESTER, NEW YORK, A CORPORATION OF NEW YORK.

FILM-DEVELOPING RACK.

1,383,733.

Specification of Letters Patent. Patented July 5, 1921.

Application filed March 27, 1919, Serial No. 285,498. Renewed December 27, 1920. Serial No. 433,429.

To all whom it may concern:

Be it known that I, NAHUM E. LUBOSHEZ, a citizen of the United States of America, residing at London, in the county of Essex, 5 England, have invented certain new and useful Improvements in Film-Developing Racks, of which the following is a full, clear, and exact specification.

My invention relates to a rack or frame 10 for supporting photographic film during the processes of developing, washing, fixing, or any other process in which the film is bathed. The object of the invention is the making of a simple and easily operated rack which is 15 efficient for the purposes described.

Reference is now made to the accompanying drawing in which like reference characters refer throughout to the same parts:

Figure 1 is a perspective view of one form 20 of my novel rack;

Fig. 2 is a perspective view of a second form;

Fig. 3 is a cross section of a portion of the 25 rack shown in Fig. 1;

Fig. 4 is a section taken on the line 4—4 of Fig. 1;

Fig. 5 is a section taken on the line 5—5 of Fig. 2, and

Fig. 6 is a section taken on the same line 30 but with the movable bar in another position.

Fig. 7 is a fragmentary detail showing a modification.

The rack comprises a rectangular frame 1, 35 which may be made of wood, fiber, or any other desired material. Upon the upper corners angle bars 2 are attached by which the rack as a whole may be supported from the edges in a suitable tank. The inner 40 edges of the sides of the frame are grooved or rabbeted, as at 3, upon one face thereof. Mounted upon the frame are two L-shaped members 4, the arms of the members extending along adjacent side bars of the frame. 45 Each member 4 has a diagonally arranged slot 5 at its elbow and also at the end of each arm. The L-shaped members or strips 4 are held against the frame 1 by screws 6 which extend through the slots 5. When the 50 L-shaped strips are moved toward the interior of the frame their edges will overhang the grooves 3, as clearly shown in Fig. 4, and when withdrawn leave the groove

open, as shown in Fig. 3. The frictional engagement between the parts is such that the 55 strip will remain in either adjusted position.

In use, the frame is laid down upon a flat horizontal surface with the strips withdrawn from above the grooves, as in Fig. 3, and the film 7 is laid in place. It is understood 60 that films and frames are supplied in sizes corresponding to each other. The movable strips are then slid over the grooves and the rack placed in the tank. In the form shown in Fig. 2, a bar 2' extends across the top and 65 its ends are used to engage the sides of the tank to support the rack 1', which consists of side bars 8, lower crossbar 9 and upper crossbar 10. In this form, which is made of sheet metal, the bars 8, 9 and 10 are struck 70 to provide a groove 3' corresponding to the groove 3 of the first described form and having the same functions. Slidable L-shaped members 4' having slots 5' are held in proper position by the screws 6'. The slots may be 75 of any desired or preferred form, such as to prevent the accidental slipping of the L-shaped members with respect to the frame. One such form of slot is shown in Fig. 7. It will be apparent that when the slot 5' is 80 in its raised position and the screw 6 in the position shown in Fig. 7 it will be less liable to slip when the inclination of the part of the slot engaging the screw is less, as shown in this figure.

The frame as a whole is simple and inexpensive in construction and exceedingly easy to manipulate, but it holds the film securely during the operations. In Fig. 1 a film 7 is 85 shown held in position and in Fig. 2 the L-shaped members are withdrawn, the rack being ready for the placing of a film therein. It is, of course, understood that this 90 frame may also be used for plates as well as films, and the term "plate" as used in the 95 claims includes any sensitized element.

Any modification included within the scope of my invention as defined in the claims are contemplated, and this disclosure is to be taken, to that extent, as illustrative.

Having thus described my invention, what I claim as new and desire to secure by Letters Patent is:

1. A developing rack comprising a frame with side and end bars, certain of said bars 105 having ledges formed upon one side and

along their inner edge upon which the edges of a plate may be laid and movable strips on said bars adapted to be moved into or out of position above said ledges.

5. 2. A developing rack comprising a rectangular frame having suspending means at one end, the bars comprising the frame having on one side along their inner edge an open groove, strips mounted on said bars to slide over said grooves so as to form therewith channels opening toward the inside of the frame.
- 10 3. A developing rack comprising a rectangular frame having suspending means at one end, the bars comprising said frame having ledges on one side and along their inner edge upon which the edges of a plate or sheet fitting within said frame may be laid, and strips slidably mounted on the bars and movable into or out of a position overlying said ledges.

4. A developing rack comprising a rectangular frame, the bars comprising said frame having rabbeted inner edges on one face and two L-shaped members mounted to 25 slide obliquely on the frame, the legs of each member when thus slid simultaneously covering or uncovering the rabbeted edges of two adjacent bars.

5. A developing rack comprising a rectangular frame, the bars comprising two adjacent sides having on their inner edges means for supporting the edges of a plate, the bars on the other two sides being rabbeted and carrying a strip having two legs 30 at right angles to each other, the legs being adapted to be slid by a single oblique motion over the rabbeted edges of the two last mentioned sides.

Signed at London, England, this 27th day 40 of February, 1919.

NAHUM ELLEN LUBOSHEZ.
